GRILLED GLASS PANEL

Archibald H. Schottland, Butler, Pa.

Application August 16, 1951, Serial No. 16,300

Term of patent 14 years

(Cl. D36—11)

To all whom it may concern:

Be it known that I, Archibald H. Schottland, a citizen of the United States of America, residing at Butler, in the county of Butler, State of Pennsylvania, have invented a new, original, and ornamental Design for a Grilled Glass Panel, of which the following is a specification, reference being had to the accompanying drawing, forming a part thereof.

Figure 1 is a face view of a grilled glass panel, showing my new design; Fig. 2 is a cross sectional view taken on the line II—II of Fig. 1, and Fig. 3 is a longitudinal sectional view taken on the line III—III of Fig. 1.

I claim:

The ornamental design for a grilled glass panel, as shown.

ARCHIBALD H. SCHOTTLAND.
